UNITED STATES PATENT OFFICE.

ALBERT BANDSEPT, OF BRUSSELS, BELGIUM.

INCANDESCENT GAS-BURNER.

SPECIFICATION forming part of Letters Patent No. 621,783, dated March 28, 1899.

Application filed September 8, 1897. Serial No. 650,953. (No model.)

To all whom it may concern:

Be it known that I, ALBERT BANDSEPT, of the city of Brussels, Belgium, have invented a new and useful Improvement in Incandescent Gas-Burners, (for which I have obtained a patent in Belgium, No. 124,988, bearing date December 5, 1896, and additions thereto, No. 125,007, dated December 7, 1896, and No. 129,205, dated July 2, 1897,) of which the following is a full, clear, and exact description.

My invention refers to Bunsen burners; and its object is to increase the quantity of air drawn in when burning town gas. This result I obtain by the combined action of gas-jets proceeding from a central or from concentric perforations gradually tapering to a point, of air-inlets situated at different heights from the gas-jet and guided by truncated cones or enlarged tubes, and of an expansion-tube the top of which—forming at the same time the top of the burner—is covered with one or more wire-gauzes, having fixed under or between them a baffle of conical shape.

In order to make my invention more clear, I refer to the annexed drawings, in which the same letters of reference denote similar parts throughout the different figures.

Figure 1 shows a section of a burner constructed according to my invention, in which I make use of a central gas-jet J and an annular jet J', situated at a lower level and issuing from a series of holes. The latter may be replaced by an annular slit J', Fig. 2, by making the gas-nozzle A of two parts so adjusted as to leave the required space between them for the passage of the gas. The gas supplied to the lower annular jet J' on issuing from the nozzle A draws in air through openings E, made in the body of the burner beneath the cone or tube C, and produces a first mixture of gas and air, while the higher central jet J increases the velocity of that mixture through the upper part of said cone, thereby producing an active suction of air through openings E'. Above the cone C is fixed a diverging or expansion tube D, the top of which is provided with wire-gauze covers G G', having fixed between them a baffle

directed into the ascending gas-current. This device has the effect of perfecting the mixture of gas and air just before entering into the flame. The cone C is fixed directly to the gas-nozzle and provided with the lower air-inlets E, Fig. 1, or it may be fixed in a special cylindrical body F, Fig. 2, in which is secured the gas-nozzle A.

Fig. 3 shows a slight modification of the burner, in which the expansion-tube D is composed of two separable parts D D'.

Figs. 4 and 5 are respectively an elevation and a section of a complete burner, showing the application of several truncated cones or tube-enlargements C C' C' at different heights and giving very good results even with a single central jet. These tube-enlargements are so arranged as to give to the air-draft the most favorable angle for obtaining the greatest sucking and mixing effect. The latter may be regulated by rings K, Figs. 2 and 3, surrounding the air-inlets and having corresponding openings. When only one single wire-gauze cover G, Fig. 5, is used, which should be of very fine mesh, the baffle B is secured under the same by means of a central plate L, Fig. 5.

The burner is, moreover, provided with a gallery M, supporting the chimney, and with a suitable support (not indicated, but fixed at N) for the attachment of the incandescence hood or mantle.

I am aware that prior to my invention truncated cones have already been proposed for guiding the air-currents in gas-burners, but they have not been combined and arranged in the specific manner described. I therefore do not claim such truncated cones broadly; but

What I claim as my invention, and desire to secure by Letters Patent, is—

1. An incandescent gas-burner, consisting in the combination of a gas-nozzle having a central and an annular perforation of inner tapered section, with a truncated conical air-chamber surrounding the gas-nozzle and having air-inlets near its base, and a burner-tube of increasing diameter toward both ends surrounding the air-chamber so as to form between itself and the air-chamber an annular

air-space and having a central conical baffle secured under the wire-gauze which covers its top, substantially as set forth.

2. In an incandescent gas-burner having its gas-nozzle surrounded by a truncated conical air-chamber: a burner-tube of increasing diameter toward both its ends, composed of a plurality of parts each having a cylindrical

portion and a funnel-shaped portion, the cylindrical portions so telescoped as to leave air-passages between them, substantially as set forth.

ALBERT BANDSEPT.
